United States Patent Office.

GEORGE W. HECKART, OF COLUMBIANA, OHIO, ASSIGNOR TO HIMSELF AND CHRISTIAN KRAMER, OF SAME PLACE.

Letters Patent No. 79,224, dated June 23, 1868.

IMPROVED HAMES-COUPING.

The Schedule referred to in these Letters Patent and making part of the same.

TO ALL WHOM IT MAY CONCERN:

Be it known that I, GEORGE W. HECKART, of Columbiana, in the county of Columbiana, and State of Ohio, have invented a new and useful Improvement in Hames-Coupling; and I do hereby declare that the following is a full and exact description thereof, reference being had to the accompanying drawings, and to the letters and figures of reference marked thereon.

The nature of my invention consists in providing a hames-coupling with two pawls, which are held in contact with the teeth of the ratchet part of the coupling by means of a spring or springs, the whole being constructed, arranged, and operating in the manner hereinafter described.

To enable others skilled in the art to make and use my invention, I will proceed to describe its construction and operation.

In the accompanying drawings, which form part of my specification—

Figure 1 is a longitudinal section of my improvement in coupling for hames.

Figure 2 is a side view of the same.

Figure 3 represents the coupling when placed on the hames.

In the drawings, A represents the case of the coupling, which is provided with a hook, B. Between the sides *o* of the case A are pivoted, at 2, two pawls, *f* and *f'*, which are, by means of a spiral spring, *x*, held in contact with the teeth *e* of the ratchet C, placed between the sides *o* of the case A, above the pawls *f* and *f'*, as shown in fig. 1. The ratchet C is provided with a hook, D. The case A, ratchet C, and pawls *f* and *f'*, may be made of wrought iron or malleable iron.

As the construction and arrangement of my improved coupling will be readily understood by reference to the accompanying drawings, I will, therefore, proceed to describe its operation.

The case A is hooked on one part of the hames, and the ratchet C is hooked on the other part. The finger-pieces *g* and *g'* are pressed together, and the ratchet C is forced into case A, so as to draw the hames into the desired position on the horse-collar. The pawls are then released, and the spiral spring *x* will force the pawls against the ratchet, so that they will catch in its teeth *e*, as shown in fig. 1.

The advantages of the two pawls *f* and *f'*, in combination with the ratchet C, are, that, should one of them become unshipped from any cause, the other pawl will hold the case A and the ratchet C together, and thereby prevent the hames from becoming uncoupled.

Having thus described the nature, construction, and operation of my improvement, what I claim as of my invention is—

A hames-coupling, constructed, arranged, and operating substantially as herein described, and for the purpose set forth.

GEORGE W. HECKART.
